ATTORNEY.

UNITED STATES PATENT OFFICE.

EDWARD C. CHAPMAN, OF PROVIDENCE, RHODE ISLAND.

WINDING-MACHINE.

1,335,426.

Specification of Letters Patent. Patented Mar. 30, 1920.

Application filed April 4, 1919. Serial No. 287,518.

To all whom it may concern:

Be it known that I, EDWARD C. CHAPMAN, a citizen of the United States, residing at Providence, in the county of Providence and State of Rhode Island, have invented a new and useful Improvement in Winding-Machines, of which the following is a specification.

This invention relates to certain new and useful improvements in a winding machine for winding a skein of yarn from a reel or creel onto a spool or bobbin, and it resides in improved mechanism for automatically arresting the winding operation upon the occurrence of a snarl in the yarn on the reel whereby the thread is prevented from breaking.

A further object of the invention is to provide means for both disconnecting the bobbin or spool from its drive and positively locking the reel from movement, and a still further object is to provide the improved mechanism whereby after the same has been arrested the reel-locking means may be reset and the yarn disentangled while the bobbin remains ineffective relative to the bobbins.

The invention further resides in the features of construction and the arrangements and combinations of parts hereinafter described in detail and claimed in a succinct manner, reference being had to the drawing wherein—

Figure 1 is an end elevation of the improved machine.

Fig. 2 is a vertical section therethrough longitudinally of the machine, depicting more clearly the bobbin drive disconnecting means, and

Fig. 3 is a detailed view of the reel arresting and locking lever.

The frame 1 has standards 2 rising from one side on which is journaled the shaft 3 that supports the creel or reel 4, and fixed to the latter, either directly or through the shaft, is a star wheel 5 having peripheral recesses 6 in which a lateral pin 7, carried on the upper end of a lock arm 8 is adapted to engage for arresting the reel from the rotation.

The lock arm is fixed on one end of a rock shaft 9 which is journaled in a bearing 10 and carries a substantially horizontal fixed arm 11 on its opposite end. This latter arm 55 is provided with a lateral lug 12 over which a latch hook 13 engages for holding the

lock arm out of the path of the star wheel. This latch hook is formed on one arm of a bell crank lever 14 pivoted at 15 to the frame 1 and carrying an upstanding thread 60 guide 16 on the outer end of the opposite arm.

An upright support 17 extends along the opposite side of the frame, and fixed on this support are spaced pairs of brackets 18 having open bearings 19 for the shafts of bobbins 20. Fixed on the bobbin shafts are drum-like or broad rimmed pulleys 21 with which the driving wheels of pulleys 22 normally have frictional contact, said drive 70 pulleys being carried on a common shaft 23 that is driven from a suitable source of power by means of the belt and pulley connection 24.

Pivoted on a bracket 25 adjacent each 75 spindle is a lever 26 having a cam terminal 27 underlying the respective drum pulley 21 and its opposite end formed into a segmental gear 28 which meshes with a segmental gear 29 formed on one end of a 80 lever 30 which is also pivoted to the bracket 25. The opposite end of this second lever 30 normally rests on the end of rock arm 11.

In most types of winders heretofore used, if the yarn on the reel becomes snarled so as 85 to prevent its drawing off freely the yarn will break thus causing a stoppage of the machine. In practice with the improved construction, the yarn is passed through the thread guide 16 whereby when the yarn 90 snarls and an excessive strain obtains thereon the thread guide is lifted to raise the horizontal supporting arm and rock the lever 14 to disengage its hook 13 from lug 12. Under the influence of a coiled spring 95 31, interposed between a ledge 32 on bearing 10 and arm 11, the latter is moved upwardly to rock shaft 9 and thereby swing the lock arm 8 into a recess 6 of the star wheel to arrest the reel from further rotation.

The upward movement of arm 11 also raises the superposed end of lever 30 to the dotted line position of the Fig. 1 which movement is imparted to lever 26 through 105 the meshing segmental gears. The cam arm 27 is thus swung into contact with and beneath the respective drum pulley 21 to elevate it out of contact with the drive pulley 22, the elongated bearings 19 permitting 110 such disengagement of the pulleys. The central bobbin in Fig. 2 indicates the man-

ner in which the drive is automatically interrupted.

The yarn is thereby saved from breaking by the automatic stopping of the particular 5 bobbin without interrupting the drive for the remaining bobbins.

The structure has a particular and important advantage in that after the winding has automatically disconnected the lock 10 arm the latch hook may be reset thus leaving the reel free to unravel the yarn and put it in operative condition before depressing the lever 30 down to the full line position to rest on arm 11. After the machine 15 is in readiness to continue the winding of the yarn the lever 30 is depressed to again seat on the arm 11 which movement swings the cam arm from under the drum pulley and permits it to drop into frictional contact with the drive pulley. 20

The operation is certain and automatic upon an abnormal strain being placed on the 25 yarn, and the construction is simple with but few parts which only operate when the thread is not feeding correctly.

Having thus described my invention, what I claim as new and desire to secure by Letters Patent is—

1. A thread winding machine comprising 30 a thread carrying reel, a notched wheel rotative therewith, a pivoted lock arm engageable with the wheel to arrest the reel, a second arm connected to the first arm, a latch hook engageable over the second arm 35 to normally hold the lock arm inoperative, a thread guide connected to the latch hook and movable by the thread passing therethrough to disengage the hook from the second arm, a lever normally resting on the 40 latter and provided with a segmental gear, a second gear meshing with the first gear, a

cam lever connected to the second gear, a bobbin adapted to be moved in its bearings by said cam lever and means for driving the bobbin and rendered ineffective by move- 45 ment of the bobbin away therefrom.

2. A thread winding machine comprising a thread carrying reel, a notched wheel rotative therewith, a pivoted lock arm engageable with the wheel to arrest the reel, a second arm connected to the first arm, a latch hook engageable over the second arm to normally hold the lock arm inoperative, a thread guide connected to the latch hook and movable by the thread passing therethrough to disengage the hook from the second arm, a bobbin for receiving the thread 50 means for driving the bobbin, and means operable by the second arm for rendering the bobbin drive ineffective. 55

3. A thread winding machine comprising a thread carrying reel, a notched wheel rotative therewith, a pivoted lock arm engageable with the wheel to arrest the reel, a second arm connected to the first arm, a 60 latch hook engageable over the second arm to normally hold the lock arm inoperative, a thread guide connected to the latch hook and movable by the thread passing therethrough to disengage the hook from the second arm, a bobbin to receive the thread, a 65 drive for the bobbin, and means operable by movement of the thread guide for disconnecting the bobbin from its drive.

In testimony whereof I have signed my 70 name to this specification in the presence of two subscribing witnesses.

EDWARD C. CHAPMAN.
